United States Patent Office.

RANSOM BULLARD AND GEORGE E. MILLS, OF LITCHFIELD, MICHIGAN.

Letters Patent No. 106,253, dated August 9, 1870.

IMPROVEMENT IN PRUNING-SHEARS.

The Schedule referred to in these Letters Patent and making part of the same

To all whom it may concern:

Be it known that we, RANSOM BULLARD and GEORGE E. MILLS, of Litchfield, in the county of Hillsdale and State of Michigan, have invented a new and valuable Improvement in Pruning-Shears; and we do hereby declare that the following is a full, clear, and exact description of the construction and operation of the same, reference being had to the annexed drawing making a part of this specification, and to the letters and figures of reference marked thereon.

Figure 1 of the drawing is a side view of my invention.

Figure 2 is a central vertical section of the same.

Our invention relates to means for pruning trees, and consists in the construction and arrangement of devices as hereinafter described, and intended to serve as useful and efficient shears for the purpose named.

A, of the drawing, represents a bar or standard, to the side of which is attached the curved arm or bracket B.

C represents a sliding bar, pivoted at its lower end to the lever D, and at its upper end to the arms G G of the shears, in the manner shown.

H is a staple, affixed to the standard A, and serves to hold the sliding bar in position.

The lever D is pivoted to the arm B and the sliding bar C, as shown, and serves as the lever by which the shears are operated.

The letter v represents a metallic plate, firmly attached to the standard.

It has a shoulder at c, that serves as a stop for the upward movements of the sliding bar, and is grooved out, as shown at y, to provide for holding and operating the blades of the shears, as hereinafter mentioned.

N N represent the two blades of our shears.

They are formed, respectively, of curved edges, as shown at w, and are pivoted in the slot y of the plate v. The lower ends of these blades are, respectively, pivoted to the arms G, as represented.

To operate our shears, the limb is grasped by the curved edges of the blades, and the unattached end of the lever D forced downward.

If the limb to be cut is situated at a great height, we sometimes operate the lever by a pitman or rod attached to the end of lever D. In that case the shoulder or stop c aids efficiently in operating the shears.

We claim as our invention—

The slotted metallic standard plate v, with shoulder c, the shear-blades N N, arms G G, bar C, curved arm B, and lever D, all constructed and arranged as described.

In testimony that we claim the above, we have hereunto subscribed our names in the presence of two witnesses.

RANSOM BULLARD.
GEORGE E. MILLS.
